UNITED STATES PATENT OFFICE

JOHN A. ADELL, OF ORANGE, MASSACHUSETTS

JACK

Application filed November 24, 1930. Serial No. 497,718.

This invention relates to a jack for use in lifting automobiles and for other lifting purposes.

The principal objects of the invention are to provide a jack having few parts, easily made of pressed sheet metal; to provide a jack which will be comparatively inexpensive to manufacture and to assemble; to protect the parts inside from dirt and to make a jack which cannot be tampered with.

Other objects and advantages of the invention will appear hereinafter.

Reference is to be had to the accompanying drawings, in which

Fig. 1 is a side view of a jack constructed in accordance with this invention and shown in its contracted position;

Fig. 2 is a similar view of the jack in expanded position, parts being broken away to show interior construction;

Fig. 3 is a plan of the jack;

Fig. 4 is a central vertical sectional view showing the interior of the jack;

Figs. 5, 6 and 7 are sectional views on horizontal lines 5—5, 6—6 and 7—7 respectively, and

Fig. 8 is a plan of the operating gear.

This jack is constructed almost entirely of pressed metal. A pressed metal base 10 is constructed with its ends at 11 raised at an angle so that the jack can be drawn over the ground readily and it has vertical sides 12 to strengthen it. To it is secured a cylindrical pressed metal casing 13. This casing is provided with integral projections 14 at a distance from the top pressed out of the material of the metal, preferably. The projections are horizontal on top and spaced apart.

On this partition rests a bevel gear 15 meshing with a pinion 16 located in a cylindrical casing 17 welded into the wall of the casing 13. This pinion is provided with a square opening 18 for a wrench or handle for operating the device. Obviously the rotation of the handle will rotate the gear 15, at a somewhat lower rate of speed.

This gear 15 is provided with a square opening 19 through it, preferably with rounded corners, and in this opening operates a vertical lifting element 20, which is

formed of sheet metal, as shown particularly in Fig. 6, formed into a substantially square shape with the corners rounded off. A screw-thread is formed on these corners which screw-thread obviously is not continuous but consists of four parts equally spaced around it. On the inside the lifting element is made with a square passage therethrough.

On the top of the casing 13 is a cap 22, flat on top and secured to the top of the casing by heading over projections 30 from the casing extending up into it. It is provided with a cylindrical nut 23 inside located centrally and threaded to receive the screw-threads 21 on the corners of the lifting element 20.

As the gear 15 rotates, the lifting element 20, which fits in the opening thereof, rotates with it and has its threads 21 meshing with the threads in the nut 23 and this element will be positively raised or lowered by its rotation.

On the inside the element 20 is also provided with a screw-thread 24 between the square corners. This also is a discontinuous thread. The nut 25 fits this thread and is provided with a hexagonal post 26 integral with it and projecting through a plate 27 freely resting on the top of the element 20 and having a hexagonal hole therethrough fitting the post 26. On the post is a work rest 28 of ordinary construction but, as shown, having grooved crossways so that there will be less opportunity for it to turn on the work. The plate 27 projects outwardly from the member 20 and it has a pair of vertical guides 29 extending down from it through a pair of openings in the cap 22 and also between the projections 14. These guides constitute means for preventing this plate and the post 26 from turning even when there is no load on the jack.

In operation, the turning of the handle turns the gear 15 which turns the lifting member 20. By reason of its screw-threads this member moves vertically in the extension or nut 23. Meantime the post 26 which is held from turning by the plate 27 is moved vertically by the fact that this screw-thread 25 meshes with the internal screw-thread 24.

It will be seen that the two screw-threads

are right-handed and left-handed respectively. Therefore the two members 20 and 26 will rise together and fall together. The plate 27 rests freely on the top of the lifting member 20 and consequently moves up and down with it, being moved down by gravity alone.

As the lifting member 20 is made of pressed metal turned up into a square tube with a seam on one side, which preferably is welded, and as the screw-threads are easily cut on it, there is very little machining and the parts are all made of sheet metal. In fact the gears also can be made of sheet metal but making these two gears does not constitute a part of this invention. The head 28 will rise twice as fast approximately as would be the case if only one screw-thread of corresponding pitch were employed. The jack is stable and the interior parts are protected from dirt and moisture by the plates 22 and 27, especially when the jack is in its contracted position and not in use. The plate 27 with its guides 29 prevents the user from rotating the post 26 and thus changing the relationship between the parts 20 and 26. These are originally arranged so that when the jack is entirely contracted the plate 27 will rest on the cap 22 and the bottom of the head 28 substantially on the plate 27. As the user cannot change this relationship, it will always come back to this position and the jack is always in condition to extend to its fullest extent.

Although I have illustrated and described one form of the invention I am aware of the fact that modifications can be made therein by any person skilled in the art without departing from the scope of the invention as expressed in the claims. Therefore I do not wish to be limited in this respect but what I do claim is:

1. In a jack, the combination with a casing having a horizontal wall therein, a gear resting on said wall, said casing having a cap fixed thereto and provided with an integral nut extending downwardly therefrom and screw-threaded inside, a vertical lifting member formed of a sheet of pressed metal in a non-circular shape with a screw-thread thereon meshing with the threads in said nut, the gear having an opening therethrough of the same shape as said lifting member whereby the lifting member will rotate with the gear, said lifting member having a thread on the interior thereof, a non-circular post within said lifting member having a screw-thread on the bottom fitting the screw-thread in the interior of the lifting member, means carried up and down with the lifting member guided by the cap and fitting the post, to prevent it from turning, and means for rotating the gear.

2. In a jack, the combination with a casing having a horizontal rest inside, and a cap

on the top of said casing fixed thereto and having a downwardly extending internal nut, of a gear located on the rest, the face of said gear engaging the bottom of said nut which receives its thrust, a lifting member having a substantially square shape passing through the gear which has an opening the same shape and size, the lifting member being screw-threaded outside to fit the screw-threads of the internal nut, a post within the lifting member having a thread, the lifting member being threaded and fitting the threads on the post, said post being hexagonal above its screw-threads, and a guide plate on the top of the lifting member having an opening fitting said post to prevent it from turning and being provided with legs extending downwardly, the cap having openings therethrough for receiving said legs and guiding them to move vertically.

3. In a jack, the combination with a casing having a horizontal partition inside integral with the casing and located above the center thereof, and a cap on the top of said casing fixed thereto and having an integral downwardly extending internal nut, of a gear on said partition, a lifting member having a non-circular shape passing through the gear which has an opening the same shape and size, the lifting member having a left-handed screw-thread outside around its corners to fit the screw-threads of the internal nut, a post within the lifting member having a right-hand thread on its bottom, the lifting member being threaded throughout its length and fitting the threads on the post, said post being non-circular above the screw-thread, a guide plate resting on the top of the lifting member and having an opening fitting said post to prevent it from turning and being provided with legs extending downwardly, the cap on the casing having openings therethrough for receiving said legs and guiding them to move vertically, and means for turning said gear.

In testimony whereof I have hereunto affixed my signature.

JOHN A. ADELL.
